UNITED STATES PATENT OFFICE.

JOHN A. MEEKER AND EMMETT J. ROACH, OF POTSDAM, NEW YORK; SAID MEEKER
ASSIGNOR TO SAID ROACH.

RECEPTACLE-SHAKING MACHINE.

Application filed March 5, 1923. Serial No. 622,798.

Milk and milk products are commonly tested to determine the percentage of butter they contain by placing a sample of the milk or product and a prescribed amount of sulfuric acid in a test bottle, which after being shaken to thoroughly mix the liquids, is placed in a centrifugal testing machine and subjected to centrifugal action in carrying out the test, which is well known in the art. 5 This invention relates to a machine adapted for shaking the test bottles to thoroughly agitate or mix the liquids therein preparatory to the centrifugal test. While the machine herein disclosed as an embodiment of 10 our invention has been designed primarily for shaking test bottles for the purpose stated, the invention is not limited to machines for this particular use, but is applicable to machines for shaking receptacles or 15 agitating material for other purposes. 20

An important object of the invention is to produce a shaking machine of the character stated, which is of very simple and inexpensive, but practical and durable construction, and which will insure a very thorough shaking and mixing of the material in the bottles or receptacles. Other objects of the invention are to simplify and improve shaking machines in the other respects herein- 25 after described and set forth in the claims. 30

In the accompanying drawings:

Fig. 1 is a plan view, partly in section, on line 1—1, Fig. 2, of a test bottle shaking machine embodying our invention.

Fig. 2 is a side elevation thereof.

Fig. 3 is a sectional elevation thereof.

Fig. 4 is an enlarged section on line 4—4, Fig. 3, showing the universal or pivotal support for the receptacle carrier.

10 represents a receptacle carrier or member in which the test bottles are placed or by which the receptacle for the material to be agitated is supported, and which is given a wabbling motion to shake and mix the contents of the receptacles or bottles. This carrier in the machine illustrated consists of a circular plate provided with a plurality of openings 11 in which bottle holders, pockets or cups 12 are secured, preferably removably. Each of the bottle holders 12 preferably consists of an open-ended metal cup which is removably retained or supported in one of the openings 11 in the carrier plate 10

50 by a flange 13 at the upper end of the cup adapted to overhang and rest upon the edge

of the opening. The holders or cups, therefore, can be readily placed in position in the openings in the carrier and removed therefrom to discharge any material which may get into the cups or for cleaning the cups. 60 Each cup is also preferably provided at one side with a tongue or inwardly protruding wall-portion 14 adapted to engage the bottle in the cup for preventing the bottle from being accidentally dislodged. The carrier 65 or member 10 could be provided with suitable holders of other kind for removable bottles or receptacles, or it could be otherwise provided with one or more receptacles to contain the material to be agitated. 70

The carrier or member 10 is loosely or movably suspended from an overhead support so that the member can swing around and tilt about its point of suspension, or have a wabbling motion. Preferably, the 75 carrier or member 10 is rigidly secured to a central shaft 15 which extends above and below the carrier and is loosely suspended at its upper end from a suitable support so that the lower end of the shaft can swing around 80 a point eccentric to the axis of the shaft to thereby produce a rotary and vertically tipping motion of the carrier. As shown, the bottle carrier plate 10 is riveted to a central hub 16 which is secured by a cross pin 17 to the shaft 15, and the upper end of the shaft projects into and is movably supported in a recess 18 in an overhead support 19, as for instance by a cross pin 20 which passes through the shaft and is seated loosely in 85 holes 21 in the support 19 at opposite sides of the shaft 15. The holes 21 are of larger diameter than the pin 20 so that the shaft is adapted to swing on the pin as a pivot and also to tilt or swing in a direction at right 90 angles to the direction of its pivotal movement on the pin 20, thereby permitting the described rotary swinging motion of the lower end of the shaft. Any other form of universal joint or suitable connection permitting a similar motion of the shaft could be employed. 95

The support 19 is preferably secured on the upper end of a stationary, upright post 22, which is fixed at its lower end to a suitable supporting frame 23. The post 22 passes through an opening 24 in the carrier 10 large enough to permit the described motion of the carrier. The frame 23 shown has a horizontal bottom portion from which 100 105 110

rises a bracket 25 provided with a laterally projecting, upper portion in which the post 22 is fixed, as for instance by a cross pin 26.

For actuating the shaft 15 to wabble or move the carrier 10, a vertical shaft 27 is preferably journalled in a bearing opening 28 in the supporting bracket 25 for the post, and this shaft is provided at its upper end with an enlargement or wheel provided with 10 an eccentric hole 29 in which the lower end of the carrier shaft 15 loosely engages. Thus, by rotating the shaft 27, the lower end of the carrier shaft 15 is caused to move in a substantially circular path of a radius determined by the eccentricity of the hole 29. Any suitable driving means may be employed for rotating the shaft 27 to operate the carrier. As shown, the shaft 27 is provided at its lower end with a pulley 30 which 20 is connected by a belt 31 to a larger pulley 32 on an operating shaft 33 journalled in a suitable bearing or support 34 on a base-board or base 5, on which the supporting frame 23 for the carrier is secured. This operating shaft can be driven either by hand or by power, as may be desired, and as shown in the drawing, the pulley 32 is provided with a crank handle 36 for rotating the shaft by hand. The operating shaft 33 is also 30 shown as being provided at its opposite end with a pulley 38 which is connected by a belt 39 to a pulley on the shaft of a suitable driving motor 40. Where a power operated machine is not required, the motor can be omitted and the receptacle carrier driven by hand by turning the pulley 32 by means of its hand crank.

Since the receptacle carrier or member 10 is rigidly secured to the shaft 15, perpendicularly thereto, and this shaft is suspended by its upper end, when the lower end of the shaft is moved in a circular path, as indicated, the carrier 10 is given a combined circulatory and up and down or wabbling motion, each of the bottles or receptacles in the carrier participating in this wabbling or rotary and tilting motion. This insures a very intimate and thorough shaking and mixture of the contents of the receptacles. 45 It will also be noted that because of the movement of the carrier about its overhead suspension point at the upper end of the carrier shaft, the lower ends of the test bottles have a greater radial motion than the upper ends or necks of the bottles. As a result, the contents tend to remain in the bottles and there is not the tendency for the contents to rise into the necks and be thrown out of the bottles, which would result by 55 an arrangement in which the bottle carrier wabbles about a point below the carrier, and which would result in a greater radial motion of the upper ends of the bottles than of their lower ends. The described construction also makes it possible to readily place

the bottles in and remove them from their holders while the machine is in motion.

We claim as our invention:—

1. In a machine of the character described, the combination of a receptacle carrier suspended from above so that it is adapted to swing around and tilt about its point of suspension, and means for so moving the carrier a receptacle adapted to contain material to be agitated, supported by the carrier and located thereon at one side of said point of suspension, said receptacle having an imperforate bottom and being vertically extended to prevent discharge of the material from the receptacle under agitation action, 75 and the upper portions of said receptacle receiving less movement than the lower portions thereof.

2. In a machine of the character described, the combination of a receptacle carrier suspended from above so that it is adapted to swing around and tilt about its point of suspension, said carrier being constructed to 85 removably retain a receptacle thereon in a location at one side of said point of suspension, said receptacle having an imperforate bottom and being vertically extended to prevent discharge of the material from the receptacle under agitation action, and the upper portions of the receptacle receiving less movement than the lower portions thereof. 95

3. In a machine of the character described, the combination of a receptacle carrier suspended from above so that it is adapted to 100 swing in an orbit around and tilt about its point of suspension, means for so moving the carrier, said carrier supporting a receptacle adapted to contain material to be agitated, said receptacle being located to swing in an orbit eccentric to the orbit of movement of said carrier, and said receptacle having an imperforate bottom and being vertically extended to prevent discharge of the material from the receptacle under agitation action. 105

4. In a machine of the character described, the combination of a receptacle carrier suspended from above so that it is adapted to swing in an orbit around and tilt about its point of suspension, and means for so moving the carrier, said carrier being provided with a pocket located to swing in an orbit eccentric to the orbit of movement of the carrier and having an open upper end 115 and adapted to receive and hold a removable receptacle, and said receptacle having an imperforate bottom and being vertically extended to prevent discharge of the material from the receptacle under agitation action. 120

5. In a machine of the character described, the combination of a receptacle carrier suspended from above so that it is adapted to swing in an orbit around and 130

tilt about its point of suspension, and means for so moving the carrier, said carrier being provided with a detachable pocket located to swing in an orbit eccentric to the orbit of movement of the carrier and having an open upper end and adapted to receive and hold a removable receptacle, and said receptacle having an imperforate bottom and being vertically extended to prevent discharge of the material from the receptacle under agitation action.

6. In a machine of the character described, the combination of a shaft movably suspended at its upper portion so that its lower portion can swing around a point eccentric to the axis of the shaft, means for so swinging the shaft, and a receptacle carrier rigid with said shaft below its point of suspension and supporting a receptacle which is located at one side of said shaft and is adapted to contain material to be agitated, and said receptacle having an imperforate bottom and being vertically extended to prevent discharge of the material from the receptacle under agitation action.

7. In a machine of the character described, the combination of a shaft movably suspended at its upper portion, means at the lower portion of the shaft for moving said lower portion in a path around a point eccentric to the axis of the shaft, and a receptacle for material to be agitated supported by said shaft and held in substantially fixed relation thereto in a position at one side of said shaft between its point of suspension and said shaft moving means, and said receptacle having an imperforate bottom and being vertically extended to prevent discharge of the material from the receptacle under agitation action.

40

8. In a machine of the character described, the combination of a shaft movably suspended at its upper portion, means for swinging the lower portion of said shaft in a substantially circular path, and a receptacle for material to be agitated supported by said shaft at one side thereof below its point of suspension, so as to swing in an orbit eccentric to the circular path of the lower end of the shaft, and said receptacle having an imperforate bottom and being vertically extended to prevent discharge of the material from the receptacle under agitation.

9. In a machine of the character described, the combination of a shaft movably suspended at its upper portion, means for swinging the lower portion of said shaft in a substantially circular path, and a receptacle carrier rigid with said shaft below its point of suspension and provided at one side of said shaft with a holder for a removable receptacle, and said receptacle having an imperforate bottom and being vertically extended to prevent discharge of the material from the receptacle under agitation action.

10. In a machine of the character described, the combination of a shaft movably suspended at its upper portion, means for swinging the lower portion of said shaft in a substantially circular path, and a receptacle carrier rigid with said shaft below its point of suspension and provided at one side of said shaft with a detachable holder adapted to receive a removable receptacle, and said receptacle having an imperforate bottom and being vertically extended to prevent discharge of the material from the receptacle under agitation action.
